SPEED CONTROL APPARATUS FOR A
FLUID-TYPE ENGINE

Charles H. Baker, Cleveland, Ohio, assignor to Cleveland
Pneumatic Industries, Inc., Cleveland, Ohio, a corpora-
tion of Ohio

Filed July 27, 1962, Ser. No. 212,831
9 Claims. (Cl. 60—24)

Broadly, this invention relates to a thermodynamic engine in which a working fluid traverses a thermodynamic cycle to produce power and more particularly pertains to a novel means for controlling the speed of the engine.

In an engine of the type disclosed herein, a working fluid compressed and heated is expanded against a working surface within an expansion chamber of a piston and cylinder arrangement to produce mechanical power. The working fluid, in an initial condition in a compression chamber, is compressed then heated and subsequently directed to an expansion chamber where it expands against the working surface. After expansion and at a reduced temperature and pressure, the working fluid is directed to a cooling heat exchanger unit where it is cooled to its initial (before compression) condition. In a fluid-type engine, the above set forth thermodynamic cycle is traversed by a suitable working fluid having desirable volumetric expansion characteristics and advantageous thermal properties. It is desirable further to provide suitable means for controlling the speed at which the fluid-type engine operates and to effectively provide such control utilizing a device which can be readily actuated to obtain the desired results.

Therefore, it is the principal object of this invention to provide apparatus cooperable with a fluid-type engine and system arrangement in which a working fluid traverses a thermodynamic cycle wherein such apparatus is operable to control the speed of the engine.

It is another object of this invention to provide apparatus cooperable with a fluid-type engine and system arrangement in which a working fluid traverses a thermodynamic cycle wherein the apparatus is operable to control the speed of the engine and is disposed intermediate the expansion chamber and the cooling heat exchanger in the system.

It is still another object of this invention to provide apparatus cooperable with a fluid-type engine and system arrangement in which a working fluid traverses a thermodynamic cycle wherein the apparatus comprises a valve and conduit arrangement operable to convey the working fluid from the expansion chamber directly to the compression chamber of the engine by-passing the cooling heat exchanger and thereby effective to control the speed of the engine.

A further object of this invention is to provide apparatus cooperable with a fluid-type engine and system arrangement in which a working fluid traverses a thermodynamic cycle wherein the apparatus controls the speed of the engine and is simple in design and construction and can be economically produced.

These and other objects and important features of the invention will be apparent from a study of the specification following taken within the drawing, which together show, illustrate, describe and disclose certain preferred embodiments and modifications of the invention and what is now considered to be the best mode of practicing the principles thereof. Other embodiments or modifications may be suggested to those having the benefit of the teaching herein, and all such embodiments or modifications are intended to be reserved as they fall within the spirit and scope of the subjoined claims.

2

In the drawing:

FIGURE 1 is a schematic illustration partially in cross-section of a system having a fluid-type engine employing a thermodynamic cycle showing apparatus incorporated therewith for controlling the speed of the engine.

FIGURE 2 is an enlarged cross-sectional view of the speed control apparatus illustrating the valve and conduit arrangement and the component parts thereof communicating the working fluid, after expansion, from the expansion chamber with the cooling heat exchanger.

FIGURE 3 is an enlarged cross-sectional view of the valve and conduit arrangement of FIGURE 2 illustrating therein the by-pass valve in a partially opened position operable in this position to convey a portion of the working fluid from the expansion chamber directly to the compression chamber by-passing the cooling heat exchanger.

Attention is now directed to FIGURE 1 of the drawing, in which a system 10 is illustrated in partial schematic form wherein the system 10 is, in effect, closed, and comprises, as a part thereof, a fluid-type engine 12 having a block 14 in which a cylinder 16 is bored and a piston 18 is reciprocably mounted. The piston 18 is secured to a connecting rod 20 and a crankshaft 22 arrangement disposed in a crankcase chamber 24 formed by a housing 26. The piston 18 comprises an enlarged base portion 28 and an extended reduced portion 30 forming a shoulder therebetween. The shoulder 32 has a working surface 34, thereon, forming one wall of a compression chamber 36 and the extended reduced portion 30 has a working surface 38 thereon forming one wall of the expansion chamber 40. The structural details of the piston 18 and the arrangement thereof with the engine block 14 are more specifically described, disclosed, shown, illustrated and claimed in the U.S. application Serial Number 213,401, filed July 30, 1962, in the name of the instant inventor and assigned to the assignee of the present invention.

The compression chamber 36 has an inlet port 42 and an outlet port 44 circumferentially spaced and suitably arranged about the engine block 14 with the ports 42 and 44 each being communicable with the compression chamber 36. The outlet port 44 has a check valve 46 communicable therewith wherein working fluid F from the compression chamber is directed through the outlet port 44 and the check valve 46 into a conduit 48 and thence into the power heat exchanger 50. Disposed intermediate the outlet valve 46 and the power heat exchanger 50 is a valve 52 and an accumulator 54 arrangement, which functions to provide rapid starting of the fluid-type engine 12 after shutdown. A detailed description of the valve 52 and the accumulator arrangement 54 is more specifically described, disclosed, illustrated, shown and claimed in the U.S. application Serial Number 222,729, filed September 10, 1962, in the name of Stanley A. Weiland and assigned to the assignee of the present invention. A conduit 56 connects the power heat exchanger 50 to an inlet valve 58 disposed adjacent one end portion of the engine block 14 in communication with the expansion chamber 40. An outlet valve 60 is also disposed at one end portion of the engine block adjacent the inlet valve 58 to provide communication of the working fluid F in the expansion chamber 40 with a conduit 62. The conduit 62 directs the working fluid F from the expansion chamber 64 therefrom through a conduit 66 into an inlet valve 68 connected to the inlet port 42 communicable with the compression chamber 36. The by-pass valve 70 is disposed in fluid communication with a conduit 74 connected to conduit 66 in the system and the specifics thereof will be described in detail hereinafter.

An oil separator 72 is connected to the conduit 62 in-

termidate the by-pass valve 70 and the cooling heat exchanger 64, wherein lubricating oil from the working fluid with which it passes through the system 10 during the operating cycle thereof is separated. The oil separator 72 is connected to a filter 73 which is connected to the engine crankcase housing 26, by suitable conduits. The lubricating oil enters into the system by conventional pumping means which directs the oil from the crankcase into the piston and through suitable passageways (not shown). Lubricating oil as directed, is thereby disposed onto the cylinder walls and into the compression chamber becoming commingled with the working fluid. The specific details of the oil separator 72 and the filter 73 in combination with the system 10 is more fully described, disclosed, shown, illustrated and claimed in the U.S. application Serial Number 191,075 filed April 30, 1962, now Patent No. 3,138,918 in the name of the instant inventor and assigned to the assignee of the present invention.

In order to compensate for certain conditions or factors, such as variations in the temperature of the working fluid F resulting from the effect created thereon by the power heat exchanger 50 and the effective cooling of the working fluid F resulting from the heat exchanger 64, as well as providing for the substitution of different types of working fluid which may be employed in the system 10 to operate the fluid-type engine 12, there is provided apparatus which may take the form of a compensator or engine "multiplier" device 75. The specific details of the compensator or engine "multiplier" are more fully described, disclosed, shown, illustrated and claimed in the U.S. application Serial Number 202,285 filed June 13, 1962, in the name of the instant inventor and assigned to the assignee of the present invention.

In order to control the speed of the fluid-type engine 12, there is provided the by-pass valve 70 and conduit arrangement disposed in the system as above set forth wherein the by-pass valve 70 (FIGURE 2) comprises a housing 76 in which is disposed an annular plate 78 pivotally mounted on a shaft 80 extending through the housing 76. Formed integral with the plate 78 is a shoulder portion 82 having a radius of curvature thereon equal to the radius of curvature of the plate 78. A porting arrangement is formed in the housing 76 wherein an inlet port 84 is in communication with the conduit 62 extending from the expansion chamber 40 of the fluid-type engine 12 and an outlet port 86 in communication with the conduit 62 extending from the by-pass valve 70 and connected to the oil separator 72. An outlet port 88 is provided in the valve housing 76 in communication with the inlet port 84 and the conduit 74 responsive to the pivotal movement of the shoulder 82. As disclosed in FIGURE 2, fluid entering the inlet port will proceed therethrough to outlet port 86 and into conduit 62 for communication with the oil separator 72 and cooling heat exchanger 64. At such time when it is desirable to control the speed of the engine, pivotal movement of the plate 78 and accordingly the shoulder 82 in a counter-clockwise direction will open port 88 in communication with conduit 74 and simultaneously reduce communication by an equal amount between the outlet port 86 and conduit 62. The control means (not shown) for imparting pivotal movement in the plate can be manually or automatically operated and accordingly depending upon the desired speed of the fluid-type engine, rotation of the plate 78 and shoulder 82 will open or close in varying degrees the fluid ports in communication with conduits 62 and 74.

In order to more clearly illustrate the inventive concept described, disclosed and shown herein by which the by-pass valve 70 and the conduit arrangement 74 is utilized to control the speed of the fluid-type engine a typical operating cycle of the engine is set forth herein. Accordingly, the cycle will be described only to the extent necessary for a complete understanding of the present invention with values for the temperatures and

pressures experienced by the working fluid F being merely exemplary and constituting representative amounts for illustrative purposes only.

In operation, a unit mass of working fluid F such as carbon dioxide at a temperature of approximately 70° F., is compressed in the compression chamber 36 to a pressure of approximately 6,000 p.s.i. and a temperature of approximately 300° F. At this temperature and pressure the carbon dioxide is directed through the outlet port 44, the outlet valve 46 and into the conduit 48. The valve 46 can be pressure responsive or actuated by suitable means (not shown) and synchronized in relationship to the cooperating elements of the cycle during engine operation. The compressed working fluid in the conduit 48 is directed through the valve 52 of the accumulator arrangement 54 and into the power heat exchanger 50 in which heat from any suitable source is applied to the working fluid F to substantially raise its temperature to approximately 500° F. while the pressure remains substantially constant. At this temperature and pressure, the carbon dioxide enters the inlet valve 58 through conduit 56 and upon synchronized opening of the inlet valve by suitable means (not shown) the working fluid F is directed to the expansion chamber 40. When the working fluid enters the expansion chamber 40, the increased volume therein provided causes the carbon dioxide to expand so that a given mass of working fluid F has a greater volume when it enters the expansion chamber 40 than it has as it is pumped out of the compression chamber 36. This expansion reduces the pressure and in turn reduces the temperature adiabatically. The piston 18 at this stage of the operation, is in the top dead-center position and upon expansion of the carbon dioxide, is moved downwardly against the connecting rod 28 and the crankshaft 22 arrangement imparting rotative movement to the crankshaft. Upon continued rotation of the crankshaft 22, through the rotation of a flywheel (not shown) attached thereto, the piston 18 is directed upwardly and the outlet valve 60 is opened allowing the escape of the expanded carbon dioxide at a reduced temperature and pressure of approximately 200° F. and 800 p.s.i. respectively, from the expansion chamber 40 into the conduit 62 through the by-pass valve 70 arrangement, as shown in FIGURE 2 of the drawing, and into the cooling heat exchanger 64. The by-pass valve, in an opened position, permits the flow of the expanded working fluid F to continue through the conduit 62 and into the cooling heat exchanger 64. Upon leaving the cooling heat exchanger 64, the working fluid F is reduced to a temperature of approximately 70° F. and a pressure of 800 p.s.i. and enters the inlet valve 68 through the conduit 66. Simultaneously with the expansion stroke, the inlet valve 68 opens to permit the carbon dioxide at the low temperature and pressure values to enter the compression chamber 36 whereupon the cycle is then repeated.

If it is desired to reduce the speed and accordingly the output of the fluid-type engine, manipulation of the plate 78 of the valve 70 in a counter-clockwise direction, will cause the shoulder 82 to provide fluid communication of the inlet port 84 through the outlet port 88 with the conduit 74. Such movement of the plate 78 will simultaneously reduce the outlet opening 86 and decrease the amount of working fluid flow from the expansion chamber 40 into the cooling heat exchanger 64. As the working fluid at the reduced temperature of approximately 200° F. and 800 p.s.i. enters the conduit 74 through the port 88 of the by-pass valve 70, the working fluid at the respective temperatures and pressures will enter the conduit 66, the inlet valve 68, inlet port 42 and the compression chamber 36 of the fluid-type engine 12. A unit mass of carbon dioxide at the respective temperature and pressure, provided after expansion in the expansion chamber will occupy a larger volume and accordingly be less dense in the available volume of the compression cham-

ber 36. Therefore, upon completion of the compression stroke of the piston 18, a lower unit pressure in the carbon dioxide will be obtained. Upon opening of the outlet valve 45 the working fluid F directed therethrough into the conduit 48 and into the power heat exchanger 50 at a relatively high temperature and low pressure and consequently will be unable to receive a quantity of heat by comparison with the working fluid directed through the cooling heat exchanger 64. The differential in the temperatures and pressures of the fluid from the expansion chamber to the compression chamber will be substantially smaller by the above recited comparison. Upon entering the expansion chamber, the fluid being at a pressure substantially less than the available pressure which could have been obtained through the entire passage of the fluid in the cooling heat exchanger 64, the working fluid will be incapable of providing the volumetric expansion equal to the expansion of the fluid experiencing the cooling stage of the cycle. Therefore, this reduction in the volumetric expansion will result in a corresponding reduction in the force imparted to the piston head 38 and thereby substantially reduce the speed of the fluid-type engine 12.

It can be readily seen that desired mixtures of fluid directed from the expansion chamber 40 into the cooling heat exchanger 64 and into the compression chamber 36 can be obtained in the range from maximum speed where the by-pass valve is closed and the shoulder 82 is completely blocking the fluid communication between the outlet port 88 and the conduit 74 to a minimum engine speed wherein the by-pass valve provides complete fluid communication of the conduit 62 leading from the expansion chamber 40 with conduit 74.

The fluid-type engine 12, as shown, discloses a single piston 18 and cylinder 16 arrangement, however, it is within the scope of the invention described herein to provide a multiplicity of such piston and cylinder arrangements within the engine block 14 and correspondingly provide a by-pass valve and conduit arrangement in communication with a system comprising a multiple piston and cylinder embodiment.

While the invention has been described, disclosed, illustrated, and shown in terms of certain embodiments or modifications which is assumed in practice, the scope of the invention should not be deemed to be limited to the precise embodiments and modifications herein described, disclosed, illustrated or shown, since other embodiments and modifications are intended to be reserved where they fall within the scope of the claims herein appended.

I claim as my invention:

1. Speed control apparatus for a fluid-type engine in which a working fluid traverses a thermodynamic cycle comprising the stages of compression, heating, expansion and cooling, said apparatus comprising:

conveying means for enabling at least a portion of such working fluid to traverse the thermodynamic cycle with such portion of the working fluid bypassing the cooling stage and passing from said expansion stage directly to said compression stage, and

control means operatively associated with said conveying means effective to control the flow of such portion of the working fluid therethrough.

2. Speed control apparatus for a fluid-type engine in which a working fluid traverses a thermodynamic cycle comprising the stages of compression, heating, expansion and cooling, according to claim 1, wherein said control means is in fluid communication with said conveying means and is selectively operable to direct such portion of said working fluid from said expansion stage through said conveying means directly to said compression stage of said cycle.

3. Speed control apparatus for a fluid-type engine in which a working fluid traverses a thermodynamic cycle comprising the stages of compression, heating, expansion and cooling, according to claim 1, wherein said conveying

means for such portion of working fluid comprises conduit means in which said working fluid flows.

4. Speed control apparatus for a fluid-type engine in which a working fluid traverses a thermodynamic cycle comprising the stages of compression, heating, expansion and cooling, according to claim 3, wherein said conduit means is connected with said fluid engine in fluid communication with said expansion stage and said compression stage of said thermodynamic cycle.

5. Apparatus for controlling the speed of a fluid-type engine in which a working fluid traverses a thermodynamic cycle comprising the sequential stages of compression, heating, expansion and cooling, said apparatus comprising:

conduit means connected to said fluid-type engine for conveying directly, said working fluid from said expansion stage to said compression stage while bypassing the cooling stage of the thermodynamic cycle, and

control means disposed in communication with said conduit means, said control means being operable to open and close fluid communication in said conduit means from said expansion stage with said compression stage of said cycle and effective upon opening to control the speed of said fluid-type engine.

6. Apparatus for controlling the speed of a fluid-type engine in which a working fluid traverses a thermodynamic cycle comprising the sequential stages of compression, heating, expansion and cooling, according to claim 5, wherein said control means comprises a valve device.

7. In combination with a fluid-type engine and system arrangement in which a working fluid traverses a thermodynamic cycle comprising the stages of compression, heating, expansion and cooling and having a piston and cylinder arrangement defining an expansion and compression chamber, apparatus for controlling the speed of said engine comprising:

means for providing communication of said working fluid from said expansion chamber directly to said compression chamber of said engine with said working fluid bypassing the cooling stage of the thermodynamic cycle, and

control means operatively associated with said means for varying said communication of said working fluid effective to control the speed of said engine.

8. In combination with a fluid-type engine and system arrangement in which a working fluid traverses a thermodynamic cycle comprising the stages of compression, heating, expansion and cooling and having a piston and cylinder arrangement defining an expansion and compression chamber, apparatus for controlling the speed of said engine according to claim 7, wherein said means for providing communication of said working fluid from said expansion chamber directly with said compression chamber and said control means comprise conduit means and a valve arrangement.

9. In combination with a fluid-type engine and system arrangement in which a working fluid traverses a thermodynamic cycle comprising the stages of compression, heating, expansion and cooling and having a piston and cylinder arrangement defining an expansion and compression chamber, apparatus for controlling the speed of said engine according to claim 8, wherein said valve arrangement is disposed in fluid communication with said conduit means and being selectively operable to direct fluid from said expansion chamber through the conduit means and into said compression chamber while bypassing said cooling stage of said thermodynamic cycle and thus effectively control the speed of said engine.
